Assistant Examiner—Kay H. Chin

Attorney, Agent, or Firm—Cislo & Thomas

[**] Term: 14 Years

[57] CLAIM

[21] Appl. No.: 921,279

The ornamental design for an aircraft landing wheel rotator attachment, as shown and described.

[22] Filed: Oct. 21, 1986

DESCRIPTION

[52] U.S. Cl. D12/345
[58] Field of Search D12/345, 319;
244/103 S

FIG. 1 is a top plan view of an aircraft landing wheel rotator attachment showing my new design;
FIG. 2 is a right side elevational view thereof, the left side elevational view being a mirror image of that shown;

FIG. 3 is a bottom plan view thereof; and

FIG. 4 is a cross sectional view taken along the line 4—4 of FIG. 1.
